(57) **CLAIM**

The ornamental design for a respiratory mask as shown and described.

DESCRIPTION

FIG. 1 is a front perspective view of a respiratory mask showing a first embodiment of our new design;
FIG. 2 is a front view thereof;
FIG. 3 is a rear view thereof;
FIG. 4 is a top view thereof;
FIG. 5 is a bottom view thereof;
FIG. 6 is a left side view thereof;
FIG. 7 is a right side view thereof;
FIG. 8 is a front perspective view of a respiratory mask showing a second embodiment of our new design;
FIG. 9 is a front view thereof;
FIG. 10 is a rear view thereof;
FIG. 11 is a top view thereof;
FIG. 12 is a bottom view thereof;
FIG. 13 is a left side view thereof; and,
FIG. 14 is a right side view thereof.

The dotted lines represent the boundary of the claim and form no part of the claimed design. The broken lines represent portions of the respiratory mask and form no part of the claimed design.

1 Claim, 12 Drawing Sheets
